WILLIAM THOMAS BUCKINGHAM ROBERTS, OF LEICESTER, ENGLAND, ASSIGNOR, BY
MESNE ASSIGNMENTS, TO UNITED SHOE MACHINERY CORPORATION, OF PATER-
SON, NEW JERSEY, A CORPORATION OF NEW JERSEY.

LASTING-MACHINE.

1,360,442.

Specification of Letters Patent. Patented Nov. 30, 1920.

Application filed December 23, 1915, Serial No. 68,382. Renewed April 14, 1920. Serial No. 373,955.

To all whom it may concern:

Be it known that I, WILLIAM THOMAS BUCKINGHAM ROBERTS, a subject of the King of England, residing at Leicester, 5 Leicestershire, England, have invented certain Improvements in Lasting-Machines, of which the following description, in connection with the accompanying drawings, is a specification, like reference characters on the 10 drawings indicating like parts in the several figures.

This invention relates to machines for use in the manufacture of boots and shoes, and more particularly to lasting and nail- 15 ing machines of the type known as hand method lasting machines, although some features of the invention are capable of use in fastening inserting machines in which no lasting elements are included. 20 The present invention has particular reference to lasting machines of the hand method type which employ instrumentalities for inserting after each pulling operation of the pincer a plurality of tacks, or 25 other loose fastenings, into the overworked shoe materials to hold the same in lasted position. A machine employing a single pincer which is caused to operate for lasting successive portions of the upper, and in 30 connection with which type of machine the present invention will be explained, is shown in U. S. Letters Patent No. 584,744; and a machine of this same type which is equipped with mechanism for inserting a plurality 35 of fastenings along the edge of the shoe at each pulling operation of the pincer, and means for rendering one or more of the devices for inserting said fastenings inoperative, is shown in U. S. Letters Patent No. 40 1,007,051.

One of the objects of the present invention is to increase the capacity of the machine shown in the last-named patent and to adapt it for operation upon a greater variety of work. To this end an important feature of the invention consists in means for inserting, at each cycle of the machine, a plurality of either of a plurality of kinds of fastenings to secure a lasted shoe upper 45 in position and means to control the insertion of either a plurality of one kind of fastening, a plurality of another kind, or a different number of either kind of fastening. 50

In machines which insert a plurality of

fastenings into the work at each cycle of the 55 operation, as exemplified in U. S. Letters Patent No. 1,007,051 above mentioned, the fastenings are ordinarily conducted from a hopper through the raceways to a tack block, or similar device, from which they are 60 driven into the work or are transferred to an adjacent fastening inserting position, and suitable tack, or other fastening separators, are employed to separate each individual fastening from the others in the race- 65 ways and permit it to pass to the openings of the tack block. Another feature of the present invention consists in improved fastening separating mechanism constructed and arranged to effect separation of the individual fastenings at a locality remote 70 from the tack block or other device to which the fastenings are passed for insertion into the work, or are transferred to an adjacent fastening inserting position. This arrangement has been found to permit of the provision of a plurality of fastening supply 75 means, such as hoppers, raceways, and separators without involving undue complications of the working parts, and without 80 necessitating the employment of small, relatively weak and easily deranged working parts, or reducing the speed at which the cycles of operation of the machines can be 85 repeated.

Another important feature of the present invention consists in a plurality of means for determining the separation of the fastenings from the sources of supply, together with a single operating member which is 90 adjustable, automatically or manually, for actuating at any one operation a selected number only of the separating means.

Another feature of the invention consists in means by which the single operating 95 member is automatically actuated through connections with the mechanism which controls the making of plaits in the upper, when lasting around the toe to take care of the fullness at that point. 100 When the plaiting mechanism is in operation said member will be so positioned as to effect the actuation of one separating means or separator controlling one raceway which contains, for example, 105 long tacks so that one long tack will be inserted in the work following each pulling operation; when the plaiting mechanism is

rendered inoperative, the member hereinbefore mentioned will be moved to a different position where it will effect the simultaneous operation of two separators which 5 control the feeding of two long tacks, which tacks will be driven into the work following each pulling operation. Another feature of the invention consists in means operated from the usual bunter or edge gage employed in this type of machine for causing the member to assume still a different position, where it will simultaneously actuate two fastening separators that control the feeding of fastenings of a different kind, for 10 example, short tacks, which are conducted from the tack hopper by two other raceways. The last-named position of the adjustable actuating member for the separators is suitable during the time that the 15 lasting operation is taking place along the sides of the shoe, and at the shank portions thereof. The bunter or edge rest being at such time pushed back from the forward position which it ordinarily occupies while 20 the lasting operation is taking place about the heel and toe portions of the shoe.

Another feature of the invention consists in means for manually adjusting the member which is automatically adjusted to different positions for controlling the supply of either one, or a plurality of long tacks, so as to effect, in addition to the above-described functions of such member, the supply of one, or a plurality of short tacks. 30 By this construction, therefore, the machine may be caused to drive one, or a plurality of long fastenings at each cycle of its operation, or one, or a plurality of short fastenings at each cycle of its operation. This 35 construction will be found particularly advantageous in those classes of work wherein it is desirable to form plaits in the upper at the shank or along the sides of the shoe, and to drive a single short fastening to secure each overworked plaited portion in position, instead of the two short fastenings which are ordinarily driven when lasting these portions of a shoe without forming plaits in the upper.

50 These, and other features of the invention, including important details of construction and combination of parts, will be more fully described hereinafter, and the novel features will be particularly pointed out in the appended claims.

Figure 1 is a side elevation, partly sectional, of a machine embodying the present invention;

Fig. 2 is a plan view, partly in section, of 60 the machine;

Fig. 3 is a front elevation of the separating mechanism for the fastenings;

Fig. 4 is a side elevation of said mechanism;

65 Fig. 5 is a plan view of said mechanism;

Fig. 6 is a side elevation, partly in section, showing certain details of the selecting mechanism under one embodiment of the invention;

Fig. 7 is a side elevation, partly in section, of the selecting mechanism, illustrating a modification, and

Figs. 8 and 9 are views in side elevation illustrating, diagrammatically, different positions of the actuating member for the 75 separator shown in Fig. 7.

Fig. 10 is a vertical section through the tack delivery plate shown in Fig. 2.

The machine comprises a column 100 upon which is supported a head 400 which carries bearings for the usual cam shaft. This shaft is provided with the usual cams for actuating the pincers 500, including the up-draw cam connected yielding to the up-draw lever from the front end of which the 80 pincers 500 are suspended; the closing cam, which operates through the usual rock shaft carried on the up-draw lever for shutting the jaws upon the upper and holding them closed while the pincers are lifted to stretch 85 the upper; and the overdraw cam which is actuated for moving the pincers inwardly over the edge of the shoe bottom to carry the pulled upper into position to be fastened. The machine is also provided with the usual, 90 or any desirable mechanism for imparting the necessary movements to the pincers 500 for forming plaits in the upper at those portions of the shoe where the fullness of the leather demands plaits, as, for instance, at 95 the toe, or when desired along the sides of the shoe. The plaiting mechanism may be controlled by devices which are operated from the usual knee lever, which lever may be supported from the shaft 56, shown in 100 section in Fig. 2. These several parts are 105 old and well known, and are shown and described, for example, in the drawings and specification of U. S. Letters Patent No. 584,744 above referred to, and to which reference may be had for a more full understanding thereof.

The shoe materials which are worked into lasted position by the pincers are secured in such position upon the shoe bottom by fastenings, such as tacks, which may be driven from the usual tack block 40 by drivers 200 which are carried by the usual driver bar 300, shown in side elevation in Fig. 1. The drivers are actuated by any suitable, or 115 usual, driver actuating mechanism such as is used in machines of this type, as, for example, the mechanism referred to in prior 120 U. S. Letters Patents Nos. 584,744 and 1,007,051. The tacks are carried in a hopper 1, which may be divided into two compartments adapted, respectively, to receive long 125 and short lasting tacks. From these compartments the raceways 2, 3, 4 and 5 are supplied, the raceways 2 and 3, for example, 130

being adapted to receive long tacks and the raceways 4 and 5 short tacks. Each pair of raceways has a detachable cover, one of which, 7, is shown in Fig. 2, said covers acting to retain the tacks in the raceways. Each raceway is provided with a reciprocating notched separator 6, see Figs. 3, 4 and 5, which is guided for reciprocating movements across the ends of the raceways, 10 and each separator is connected by a transverse bar with one of four studs 8, 9, 10 and 11, which project, respectively, from the bars 12, 13, 14 and 15, said bars being guided for reciprocating movements in openings 15 formed in brackets 17, 18, which project rigidly from a portion of the machine frame. The ends of the raceways and the separators are covered by detachable covers 19, 20, 21 and 22 which are secured in 20 position thereon by screws, or other suitable fastenings.

A plate 23, provided with an opening 24 opposite each raceway, is arranged to be reciprocated across the ends of the raceways, 25 and to pass between each separated tack and the next one in the raceway and insure that the separated tack remains upright. The plate 23 is connected by a link 25 to a rod 26 which is mounted to slide in the 30 brackets 17 and 18 and carries a cross bar 27 at one end which bears upon the extremities of the rods 12, 13, 14 and 15. A spring 28 surrounds the rod 26 and bears at one end against the inner side of the bracket 18, 35 while at its opposite end the spring has bearing against a collar 29 which is adjustably secured on the rod 26. The spring is confined under tension between the bracket 18 and collar 29, and acts to yieldingly, 40 maintain the rod 26 and, through the intermediary of the cross bar 27, the rods 12, 13, 14 and 15, in the positions shown in Fig. 3. The separators and their associated parts are supported upon a bracket carried by the 45 machine frame, and a passage 30 is formed in said bracket opposite the end of each raceway, as shown in Figs. 1 and 5. Each passage 30 is connected by a short pipe 31 with one of a plurality of tack tubes 32, 33, 34 and 35, herein represented as four in number, which are adapted to conduct the separated tacks to openings in the tack block 40, Fig. 1. The tack tubes are shown as being carried by a bracket 36 which is provided 50 with an opening arranged to receive a supporting stud 37, carried rigidly by the machine frame, whereby the bracket may be slid into position by a lateral movement. A bracket 39, carried rigidly by the machine 55 frame, has a threaded opening to receive a set screw 38, and the end of said screw has bearing upon a lug projecting from the bracket 36 so that when the screw is turned, the bracket 36 may be clamped into position 60 with the ends of the tubes 32, 33, 34 and 35.

properly aligned with the ends of the short pipes 31. The lower ends of the tubes 32, 33, 34 and 35 are connected with a plate 86, which is received in a recess formed in the block 41. Immediately below the plate 86 two passages are formed in the block 41 opposite the ends of the tubes 32 and 34, which passages unite in a single passage 87, adapted to discharge tacks into a single orifice of the tack block 40 when the latter is in its rear-most position. The block 41 is also provided with two passages opposite the ends of the tubes 33 and 35 which unite into a single passage 88 adapted to discharge tacks into the other receiving orifice of the 80 tack block 40. The block 41 in which these passages 87 and 88 are formed is provided with a threaded shank 88' which passes through a hole in the lower portion of the bracket 36, and a milled nut 42 has an internal thread engaging the threaded shank 88' for thereby holding the block 41 upon the bracket 36. The block 41 may be readily removed from the bracket 36 by removing the nut 42 from its threaded shank. 90

A bracket 43, carried by the machine frame, pivotally supports a hollow shaft 44 having, at its lower end, a fork 45. This fork carries a shaft 46 upon which are pivoted two cams 47 and 48. The cam 47 is 95 connected by a ball and socket joint to a rod 49, which has its other end connected by a ball and socket joint with an arm 50, formed as an extension of an arm 51 which is pivotally supported upon a shaft 52. The 100 arm 51 is connected through a spring-pressed rod 501 with the usual bunter edge rest 53 of the machine which slides backwardly and forwardly in a fixed track, and is held yieldingly by the spring in its forward position as shown in Fig. 1. When the bunter edge rest occupies this position the cam 47 and its associated parts are located as shown in Fig. 6. The cam 48 is connected by a ball and socket joint to one 110 end of a rod 54 whose opposite end is connected by a ball and socket joint to an arm 55, which is rocked about a vertical pivot 56 by connections (not shown) to the plaiting mechanism of the machine when this 115 mechanism is thrown into or out of operation. In Figs. 1, 2 and 6 of the drawings the parts are shown in the positions which they occupy when the plaiting mechanism is out of operation. 120

A rod 57 is mounted for sliding movement within the hollow shaft 44, and its lower end projects within the fork 45 and is of sufficient width to engage either of the cams 47 and 48. The upper portion of the 125 rod 57 is provided with a recess which receives a spring 58 confined between a transverse pin 59 carried by the shaft 44, and the bottom wall of said recess, and said spring acts to urge the rod 57 downwardly 130

into yielding engagement with the cams 47, 48. The rod 57 is provided with a socket to receive one end of a lever 60, which is fulcrumed at 61 in a supporting sleeve 62 which is mounted to turn upon the shaft 44. A plunger 63 is urged yieldingly upward against the inner end of the lever 60 by a spring 64 which is received in a recess in the lower portion of the rod 57. The springs 58, 64 act yieldingly in opposite directions against the inner end of the lever 60, so that if the rod 57 is moved in either direction at a time when the lever 60 is not free to turn about its pivot 61 damage to the parts will be avoided.

The lever 60 has an enlarged end 68 which is adapted to coact with the ends of the rods 12, 13, 14 and 15, in a manner to be herein-after described, for operating the tack separators. The swiveled support 62 has two rigid projections 65 and 66, as shown in Fig. 2, through which are threaded adjusting screws 69 and 70 arranged to bear upon opposite sides of an operating lever 67 which is pivoted upon the shaft 44, and is adjustable with reference to the lever 60 by the screws 69, 70. A shaft 73, which is carried in bearings supported by the machine frame and is driven by suitable connections from the main power shaft, carries a cam which is provided with a cam roll 71 arranged to engage a flat portion 74 at the end of the lever 67 and acts, when shaft 73 is rotated, to impart an oscillating movement to the lever 67. A spring 75, which extends between the frame of the machine and the lever 67, acts to hold the flat portion of the lever in yielding engagement with the cam roll, and thus coöperates therewith in imparting oscillating movements to the lever. The oscillating movements of the lever 67 are transmitted through the instrumentality of the projections 65, 66, set screw 69, 70, and support 62 to the separator actuating lever or member 60, which in turn effects reciprocating movements of those separators which are selected for operation in accordance with the position of the lever 60. It will be observed that, by reason of the springs 28 and 75, the separators will be operated yieldingly in both directions, and hence damage to the parts in the event of any partly separated tack becoming jammed between the separators and raceways, will thereby be avoided.

It is desirable that the timing of the cam 71 and associated parts be such with relation to the cycle of operation of the machine that actual separation of the tacks will be effected in the early stages of the cycle of operation and not, as is customary in hand method lasting machines as heretofore constructed, toward the latter portion of the cycle since by separating the tacks in the same cycle of operation as that in which

they are inserted in the work any desired change in tack supply can be obtained in the cycle next succeeding the making of the adjustment for producing the change. This subject-matter, however, forms no part of the present invention as the same is claimed in co-pending application Serial No. 70,169, filed January 4, 1916, which eventuated in United States Letters Patent No. 1,268,357, granted June 4, 1918, on application of Jerram and Keall.

By reason of the fact that the separating devices are located remote from the tack block, and especially where the timing of the separating devices is of the character above indicated, it may be desirable to accelerate the passage of the separated tacks through the tack tubes 32, 33, 34, and 35 by a blast of air to be directed into the tubes at the appropriate time. An air pump 76, shown by full lines in Fig. 1 and by dotted lines in Fig. 2 of the drawings, may with advantage be utilized for this purpose, and this pump could be conveniently operated through a bevel gear 77 to be driven by a bevel gear 72 fast on the shaft 73, and a shaft 78 carrying the gear 77 could be provided with suitable connections for driving the pump. This feature forms no part of the present invention, but is fully described and claimed in said last mentioned patent.

Referring now to the operation of the cams 47, 48, it will be observed that when they occupy the position shown in Fig. 6 the rod 57 is not in engagement with the cam 47, but rests upon the high part of the cam 48 in which position the enlarged end 68 of the lever 60 is located opposite the ends of the rods 12 and 13, and upon operation of the machine the lever will, while in this position, effect separation of the long tacks from the raceways 2 and 3. This is the position that these parts would occupy with the bunter edge rest 53 forward and the plaiting mechanism of the machine inoperative, as when the heel seat of a boot or shoe was being lasted. Because of the thickness of the shoe material at the heel end of the shoe it is desirable at this time to insert two long tacks at each cycle.

During the time that the lasting operation is being performed at the toe end of the shoe and the plaiting mechanism is in operation, the rod 54 will be moved through its connections with the plaiting mechanism, either to the right, or to the left, from the position which this rod is shown as occupying in Fig. 6, thereby moving cam 48 to the right or to the left, and permitting the rod 57 to be forced by its spring 64 on to a low portion of the cam 48. This will result in raising the outer end of lever 60 so that its enlarged portion 68 will be opposite the end of the rod 12 only, as shown by the broken lines in Fig. 6, and in this position when

lever 60 is actuated to effect tack separation a single long tack will be separated from the raceway 2 at each cycle.

When the lasting operation is being performed along the sides, or at the shank of the shoe, the bunter edge rest 53 will be pushed in, as is usual when operating at these portions of a shoe thereby, through the connections described, moving rod 49 to the left, Fig. 6, and cam 47 to the right to raise the rod 57 and move the lever 60 into the lower position indicated by broken lines, with its enlarged end 68 opposite the rods 14 and 15. When the lever 60 is then operated to effect tack separation two short tacks will be separated from the tacks in the raceways 4 and 5 at each cycle of operation. Inasmuch as the cam 47, in this embodiment of the invention, has a greater throw than the high portion of cam 48 the position of lever 60 which is caused by the retracted movement of the bunter edge rest 53 to effect the separation of two short tacks at each cycle will be unaffected by the throwing into or out of operation of the mechanism to cause plaiting, and hence if it is desired to form plaits in the leather when lasting at the shank or sides of a shoe the plaiting mechanism can be caused to operate while two short tacks are being inserted following each pull, and this may be desirable when lasting these portions of a shoe.

Referring to the modified construction shown in Figs. 7, 8 and 9, the swiveling support 62 is, under this embodiment of the invention, provided with a bearing 79 for a rotatable disk 80 which is provided with an adjusting handle 81 and carries an eccentric stud 61' which forms the axis about which the lever 60 is adjusted to co-act with the several rods 12, 13, 14 and 15 connected with the separators. A fulcrum block 82 is pivotally mounted upon the stud 61' and engages a slot 83 formed in the lever 60. It will be seen that by rotation of the handle 81 the position of the end of the lever 60 with relation to the ends of the rods 12, 13, 14 and 15 can be manually adjusted so as to effect modifications of the automatic adjustments of the lever which are effected through the action of the cams 47' and 48. In this embodiment of the invention the cam 48 is substantially of the same construction as the cam 48 in the form of the invention illustrated in Fig. 6; the cam 47', however, which is connected with the bunter edge rest of the machine, is of a somewhat modified construction in that its highest part is so designed as to impart a movement to the rod 57 which will be equal in extent to the movement imparted to said rod by the high part of the cam 48.

Referring to Fig. 7, the parts are shown in the position which they will occupy with the bunter edge rest forward and the plait-

ing mechanism inoperative, the rod 57 in such case resting upon the high part of the cam 48 and serving to set or position the lever 60 as it is shown by full lines, with its enlarged end opposite the ends of the rods 12 and 13 for supplying long tacks from the raceways 2 and 3, at each separating actuation. With the cams 47' and 48 in this same position, the disk 80 may be rotated clockwise by its handle 81 to move the stud 61' downwardly into the position shown in Fig. 8 of the drawings. By this movement of the stud 61', the lever 60 will be set with its outer end opposite the rods 14 and 15 in position to effect separation of two short tacks, one from each of the raceways 4 and 5. If the plaiting mechanism is then rendered operative and hence the cam 48 moved in one direction or the other so as to permit the rod 57 to be depressed on to one or the other of the low portions of the cam, the lever 60 will be caused to assume the position indicated by broken lines in Fig. 8 for effecting the separation of a single short tack. If the disk 80 is rotated still farther in the same direction, the stud 61' will be set in the position shown in Fig. 9. The lever 60, however, will still be in position to effect the separation of two short tacks when the plaiting mechanism is inoperative, but when the plaiting mechanism is rendered operative, the lever 60 will assume the position shown in the dotted lines in Fig. 9 to effect the separation of one long tack.

It is to be noted that when the stud 61' has been moved to the inner end of the slot 83, as shown in Fig. 9, the outer end of the lever 60 will be moved a greater distance with a given movement of the inner end of the lever than said lever will be moved when its fulcrum point 61' is adjusted near the outer end of the slot 83, as shown in Figs. 7 and 8, and that the disk 80 is turned through an angle of approximately 180° in moving the stud 61' from the position which it is shown as occupying in Fig. 7, to the position shown in Fig. 9.

When the bunter edge rest 53 is moved backward by pressure of the shoe when lasting along the side or shank and the high part of the cam 47' is moved under the rod 57, the lever 60 will be set to effect, irrespective of whether the plaiting mechanism is operative or inoperative, separation of long tacks from the raceways 2 and 3, when the stud 61' is positioned as shown in Fig. 7, and to effect separation of short tacks from the raceways 4 and 5 when the stud is positioned as shown in Fig. 8, or 9.

It is thought that the operation of the machine, and the effects of the different adjustments of the tack separating mechanism, have been sufficiently set forth in connection with the foregoing description of the construction and relative arrangement

of the various parts of the machine to be understood without further description.

While the invention is herein shown and described as embodied in a lasting machine 5 in which preferably loose tacks are driven for securing the lasted shoe materials in position, it will be obvious that many features of the invention may be employed with advantage in other machines and that it is 10 not essential to the invention what kind of fastenings are handled by the machine.

Having described the invention in connection with two of its preferred embodiments, what I claim as new and desire to 15 secure by Letters Patent of the United States is:—

1. A machine of the class described having, in combination, means for lasting an upper, means for supplying a plurality of 20 kinds of fastenings for use in securing the lasted portions of the upper in position, and means to control the insertion during a single cycle of the machine of either a plurality of one kind of fastening, or a different number of another kind of fastening.

2. A machine of the class described having, in combination, means for lasting successive portions of an upper, means for supplying a plurality of kinds of fastenings and means to control the kind of fastenings inserted and also for controlling the 30 number of fastenings inserted at each cycle of operation of the machine to secure in position each lasted section of the upper.

3. A machine of the class described having, in combination, means for lasting an upper by successive operations, means for supplying two kinds of fastenings, and 40 means to control the insertion of one or a plurality of either kind of fastening at each cycle of operation for fastening each lasted portion of the upper in position.

4. A lasting machine having, in combination, pincers and means for actuating them to seize, pull and release an upper, means for supplying a plurality of kinds of fastenings, and means to control the insertion of one or a plurality of one kind of fastening or a plurality of another kind of fastening for each cycle of the pincers.

5. A lasting machine having, in combination pincers and actuating means to cause the pincers to seize, pull and release an upper mechanism to effect plaiting movements of the pincers, means for supplying long and short fastenings, and means to effect the insertion of one long fastening at each pincer cycle when the upper is being lasted 55 and plaits are formed at the toe end of a shoe and two long fastenings at each cycle when the plaiting is discontinued, and to effect the insertion of two short fastenings at each cycle when the upper is being lasted 60 and at the sides of the shoe.

6. A lasting machine having, in combination, pincers and actuating means to cause them to seize, pull, and release an upper, plaiting mechanism, means for supplying long and short fastenings, means connected with said mechanism to control the insertion of one or a plurality of long fastenings at each cycle, an edge rest, and connections to control the insertion of short fastenings by movement of said edge rest. 75

7. A machine of the class described having, in combination, lasting devices including pincers, mechanism to cause the pincers to plait an upper, means for supplying long and short fastenings, means connected with 80 said mechanism to control the insertion of one or a plurality of long fastenings at each cycle, a movable edge rest, and means connected with said edge rest and arranged to cause the insertion of short fastenings at 85 each cycle when said rest is retracted, regardless of whether the plaiting mechanism is operative or inoperative.

8. A machine of the class described having, in combination, lasting devices including pincers, mechanism to cause the pincers to plait an upper, means for supplying long and short fastenings, means to control the insertion of one or a plurality of long fastenings at each cycle according to the position of the plaiting mechanism, an edge rest, and connections to control the insertion of short fastenings at each cycle when 95 said rest is retracted regardless of the position of the plaiting mechanism.

9. A machine of the class described having, in combination, lasting means for operating successively upon different portions of an upper, a plurality of sources of supply for fastenings, a plurality of devices for determining the separation of the fastenings from said sources of supply, and a member arranged for adjustment to actuate, at each cycle of operation, a selected plural number 100 of said separating devices.

10. A machine of the class described having, in combination lasting means for operating successively upon different portions of an upper, a plurality of raceways for conveying fastenings into position to be driven, driving means, independent separators for controlling the delivery of fastenings from said raceways, and a single operating member arranged for adjustment to selectively operate the desired separators at each cycle 115 of operation of the machine.

11. A machine of the class described having in combination, lasting means for operating successively upon different portions of an upper, a plurality of raceways for conveying different kinds of fastenings from separate sources of supply into position to be driven, driving means, independent separators for controlling the delivery of fastenings from said raceways, and a single 125

5 operating member for the separators adjustable to different positions for determining the number and kind of fastenings to be driven at each cycle of operation of the machine.

10 12. A machine of the class described having, in combination, lasting means for operating successively upon different portions of an upper, a plurality of raceways for conveying different kinds of fastenings to position to be driven, a separator for each raceway, a member arranged for adjustment to operate selectively the desired separators at each cycle, yielding means for imparting 15 adjusting movements to said member, and means to impart separator actuating movements to said member.

20 13. A machine of the class described having, in combination, lasting means for operating successively upon different portions of an upper, a plurality of raceways for conveying different kinds of fastenings to position to be driven, a separator for each raceway, an adjustable member arranged to be 25 positioned for actuating one or a plurality of the separators for each kind of fastening to be driven at each cycle of operation, and actuating means for said member.

30 14. A lasting machine having, in combination, a pincer, operating mechanism therefor arranged for adjustment, means for supplying long and short tacks, tack driving means adapted to insert one or a plurality of long tacks for each operation of the pincer, according to the adjustment of said mechanism, and an edge rest arranged for adjustment to cause insertion of short tacks.

35 15. A lasting machine having, in combination, a pincer, operating mechanism therefor arranged for adjustment, means for supplying long and short tacks, tack driving means adapted to insert one or a plurality of long tacks for each operation of the pincer according to the adjustment of said mechanism, an edge rest arranged for adjustment by pressure of a shoe to cause the insertion of a plurality of short tacks at each pincer operation, and manually controllable means to vary the number of short tacks inserted.

40 16. A lasting machine having, in combination, a pincer, operating mechanism therefor arranged for adjustment, means for supplying two kinds of fastenings, fastening driving means adapted to insert a plurality of one kind of fastening for each operation of the pincer and arranged to have the number of said fastenings varied with the adjustment of the pincer operating mechanism, an adjustable edge rest for controlling the insertion of a different kind of fastening, and manually operable means for varying the number and kind of fastenings to be inserted.

45 17. A lasting machine having in combination, a pincer, operating mechanism therefor

5 arranged for adjustment, fastening driving means, raceways for supplying a plurality of kinds of fastenings, a separator for each of said raceways, an operating member for said separators arranged for adjustment concurrently with the adjustment of the pincer 10 operating mechanism to control the number of one kind of fastening inserted at each operation of the pincer, an edge rest arranged to cause the insertion of a different kind of fastening, and manually-controllable means 15 to vary the number of the last-named fastenings inserted at each operation of the pincer.

18. A lasting machine having, in combination, lasting means for operating successively upon different portions of an upper, means for inserting a plurality of either of two kinds of fastenings to secure each lasted portion of the upper in position, and means to control the number and kind of fastenings 20 inserted at each lasting operation.

19. A lasting machine having, in combination, lasting means for operating successively upon different portions of an upper, means for inserting one or a plurality of long or short tacks to secure each lasted portion of the upper in position, and means including an adjustable member, to control the number and kind of tacks inserted at each lasting operation.

20. A lasting machine having, in combination, a pincer and operating mechanism therefor arranged for adjustment, a plurality of raceways for conveying two kinds of fastenings, independent separators for 100 the raceways, reciprocating rods connected with said separators, a pivoted actuating member arranged for adjustment into operative relation with any of said rods, according to the number and kind of fastenings to 105 be inserted to each cycle, means to adjust said member in position to deliver one or a plurality of one kind of fastening, and means controlled by pressure of the work to adjust said member in position to deliver 110 a plurality of a different kind of fastening.

21. In a machine of the class described, the combination with raceways and tack separators, of a tack block, a plurality of 115 conduits for conveying the tacks from the separators to the tack block, a stud on the machine frame, and a carrier supporting said conduits and having an aperture fitting said stud to permit the carrier to be inserted 120 into or removed from position by a lateral movement, and clamping means for securing said carrier in position.

22. In a machine of the class described, the combination with a tack block, of a plurality of conduits for tacks, and a block having openings in communication with said conduits, pairs of which openings unite each

- in a single opening through which the tacks are delivered to the tack block.
23. In a machine of the class described, the combination with a plurality of raceways, tack separators therefor, reciprocating rods connected with said separators, yielding means for holding the separators in position to prevent the discharge of tacks from the raceways, an actuating member arranged for adjustment into operative relation with any of said rods to effect the discharge of tacks from the selected raceway or raceways, means for yieldingly actuating said member, and tack driving means.
- 15 24. In a lasting machine, the combination with a pincer and operating means therefor, a plurality of raceways, tack separators therefor, reciprocating rods connected with said separators, yielding means for holding 20 the separators in position to prevent the discharge of tacks from the raceways, a pivoted actuating member adjustable to position one end in operative relation with one or a plurality of said rods to effect the discharge of tacks from the desired raceway or raceways, a reciprocating rod in yielding engagement with the other end of said member, an edge rest, cams for actuating said rod in accordance with the position of 25 said pincer operating means and edge rest, and tack driving means.
25. In a machine of the class described, the combination with tack raceways for supplying a plurality of kinds of tacks, tack 30 separators therefor, reciprocating rods connected with said separators, an actuating member adjustable for selectively operating said rods according to the number and kind of tacks to be inserted at each operation of 35 the machine, means for operating said member to deliver tacks including a yielding element to prevent injury to the parts if a tack should become jammed, and tack driving means.
- 40 45 26. A lasting machine having, in combi-

nation, a pincer, means for imparting successive lasting movements thereto, a plurality of raceways for supplying two kinds of tacks, tack driving means, and automatic means, under the control of the operator, to determine the kind of tacks and also the 50 number of tacks which will be inserted at each pincer operation.

27. A lasting machine having, in combination, a pincer, means for imparting successive lasting movements thereto, a plurality of raceways for supplying two kinds of tacks, tack driving means, means to determine the kind and number of tacks to be 55 inserted at each operation of the pincer, and manually operable means for modifying the action of said means.

28. A lasting machine having in combination, a pincer, operating means for imparting successive lasting movements thereto, a plurality of raceways for supplying two kinds of tacks, tack driving means, a movable edge rest, means arranged for adjustment coincidently with the movement of the edge rest to determine the number and kind 60 of tacks which will be inserted at each operation of the pincer, and manually operable devices to modify the action of said last named means.

29. In a machine of the class described, the combination of means for inserting fastenings singly, means for inserting other fastenings in couples, and means for selectively determining which of said fastenings 75 shall be inserted.

30. In a machine of the class described, the combination of means for working an upper over a last, and means for selectively inserting single fastenings of one kind or 80 two fastenings of another kind at a single 85 cycle of the machine operation.

In testimony whereof I have signed my name to this specification.

WILLIAM THOMAS BUCKINGHAM ROBERTS.
